[57] **CLAIM**

The ornamental design for a boot jack or similar article, substantially as shown and described.

DESCRIPTION

FIG. 1 is a perspective view of boot jack or similar article, showing my new design,

FIG. 2 is a front elevational view thereof,

FIG. 3 is a top plan view thereof,

FIG. 4 is a reduced scale rear elevational view thereof,

FIG. 5 is a cross sectional view taken on the line 5—5 of FIG. 2,

FIG. 6 is a fragmentary cross sectional view taken on either one of the two lines 6—6 of FIG. 2,

FIG. 7 is a fragmentary cross sectional view taken on either one of the two lines 7—7 of FIG. 2,

FIG. 8 is a fragmentary cross sectional view taken on either one of the two lines 8—8 of FIG. 2,

FIG. 9 is a front elevational view of another embodiment of the boot jack or similar article shown in FIGS. 1—8 with the four areas between the spokes being padded; and,

FIG. 10 is a cross sectional view taken along line 10—10 of FIG. 9.

FIG.1.

FIG.2.

FIG.3.

FIG. 5.

FIG. 4.

FIG. 7.

FIG. 8.

FIG. 6.

FIG. 9.
